PAN GREASING BRUSH

James M. Wilde, Philadelphia, Pa.

Application April 21, 1941, Serial No. 389,657

5 Claims. (Cl. 15—128)

The present invention relates to new and useful improvements in fountain brushes designed primarily for use in greasing baking pans and the like, and has for its primary object to provide a brush of this character adapted to more effectively enter the corners of the pan for properly greasing the same.

A further object of the present invention is to provide a brush mounting including a substantially conical cap having a plurality of brush sections mounted therein adapted for engaging the bottom of the pan, the brushes projecting in diverging relation and adapted for spreading into the corners of the pan when the pan is placed in position on the brush, and also to provide means for easily and quickly detachably securing a plurality of brushes on the brush mounting for wiping against the side walls of the pan during the greasing operation.

A still further object is to provide a device of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which—

Figure 1 is a side elevational view.

Figure 2 is a similar view with the side brushes removed and with the cap detached from the mounting.

Figure 3 is a bottom plan view, and

Figure 4 is a top plan view.

Referring now to the drawing in detail, wherein for the purpose of illustration I have disclosed a preferred embodiment of the invention, the numeral 5 designates a brush mounting generally which includes upper and lower brush supporting plates 6 and 7 respectively, connected by a grease feed tube 8. The peripheral edges of the plates 6 and 7 are provided with aligned slots 9 disposed vertically and adapted for receiving the substantially rectangular-shaped brush heads 10 with the bristles 11 of the brush projecting radially from the mounting and extending in a vertical position.

The brush is preferably constructed with three sets of the vertically extending brushes 10 and the brushes are connected by a coil spring 12 to yieldably maintain the heads of the brushes in the slots 9.

On top of the plate 6 is a conical cap 13 provided with a short pipe 13' fitted in the upper end of the tube 8 and secured thereto by a set screw 13'', the cap being preferably constructed of a plastic material and within which three sets of bristles 14 are embedded, with the bristles extending substantially at right angles to the surface of the cap and with their outer ends in diverging relation. Likewise, the outer ends of the bristles taper into a substantially pointed extremity as indicated at 15. The sets of bristles 14 likewise are positioned between the vertically extending brushes 10.

To the under side of the lower plate 7 is secured a socket 16 adapted for connection with a grease supply pipe (not shown) the grease being forced under pressure through the tube 8 and outwardly through the passage 17 formed in the top of the cap 13. Likewise the surface of the cap 13 is formed with channels 18 leading from the passage 17 toward the vertical brushes 10.

In using the device, the bread pans are placed over the brush assembly, thus causing a spreading of the brushes 14 against the bottom of the pan and into the corners thereof. At the same time, the vertically extending brushes 10 serve to wipe against the side walls of the pan and by arranging the brushes 10 in substantially triangular form in cross section, as shown to advantage in Figures 3 and 4 of the drawing, the bristles 11 of the brushes 10 are adapted to also enter the corners of the pan to effectively grease all portions of the pan.

The loose mounting of the brushes 10 in the slots 9 enable the brushes be easily and quickly removed and replaced when desired.

It is believed the details of construction, advantages and manner of use of the device will be readily understood from the foregoing without further detailed explanation.

Having thus described the invention, what I claim is:

1. A pan greasing brush comprising a mounting having a conduit extending therethrough, one end of the mounting being adapted for attaching to a grease supply pipe and the other end of the mounting having a grease discharge port, a plurality of groups of bristles secured in diverging relation to the mounting at its end adjacent the discharge port sockets at circumferentially spaced points on the sides of the mounting and a plurality of brush units secured in said sockets, said brush units extending longitudinally of the mounting and projecting radially therefrom.

2. A pan greasing brush comprising a pair of circular plates, a grease feed tube connecting the plates in spaced relation, means carried by one of the plates for attaching to a grease supply pipe, a cap on the other plate having a discharge port communicating with the tube, outwardly diverging groups of bristles secured to the cap, alined sockets in the edges of the plates and brushes having heads removably positioned in said sockets.

3. A pan greasing brush comprising a pair of circular plates, a grease feed tube connecting the plates in spaced relation, means carried by one of the plates for attaching to a grease supply pipe, a cap on the other plate having a discharge port communicating with the tube, outwardly diverging groups of bristles secured to the cap, alined sockets in the edges of the plates, brushes having heads removably positioned in the sockets and spring means connecting the heads of said brushes.

4. A pan greasing brush comprising a pair of circular plates, a grease feed tube connecting the plates in spaced relation, means carried by one of the plates for attaching to a grease supply pipe, a conical cap of plastic material carried by the other plate and having a discharge port communicating with the tube, a plurality of groups of bristles projecting from the surface of the cap in diverging relation and a plurality of brushes 10 attached in spaced relation to the edges of the plates.

5. A pan greasing brush comprising a core having a feed passage therein for discharging grease at one end of the core, brush units projecting in diverging relation at said discharge end of the core and brush units extending longitudinally at the sides of the core and arranged in triangular cross-sectional relation with respect to the core and longitudinally between the first- 15 named brush units.

JAMES M. WILDE.
